UNITED STATES PATENT OFFICE

FRANK E. WAKEFIELD, OF ELGIN, ILLINOIS, ASSIGNOR TO LUCIEN LELONG INC., OF CHICAGO, ILLINOIS, A CORPORATION OF ILLINOIS

DESIGN FOR A POWDER CONTAINER OR SIMILAR ARTICLE

Application filed May 26, 1930. Serial No. 35,776. Term of patent 7 years.

To all whom it may concern:

Be it known that I, FRANK E. WAKEFIELD, a citizen of the United States, and a resident of the city of Elgin, in the county of Kane and State of Illinois, have invented a new, original, and ornamental Design for a Powder Container, or Similar Article, of which the following is the specification, reference being had to the accompanying drawings, forming a part hereof.

In the drawings:

Figure 1 illustrates an isometric view of

the powder container, or similar article, embodying my invention.

Figure 2 is a top plan view thereof.

The appearance of the container is enhanced by contrasting colors distinguishing the body and marginal portions of the sides and top thereof.

I claim:

The ornamental design for a powder container, or similar article, as shown and described.

FRANK E. WAKEFIELD.
